UNITED STATES PATENT OFFICE.

DAVID B. WILSON, OF GARY, INDIANA.

HORSEMAN'S COAT.

1,330,152.

Specification of Letters Patent.

Patented Feb. 10, 1920.

Application filed June 14, 1918. Serial No. 239,968.

To all whom it may concern:

Be it known that I, DAVID B. WILSON, a citizen of the United States, residing at Gary, in the county of Lake and State of Indiana, have invented certain new and useful Improvements in Horsemen's Coats; and I do hereby declare the following to be a full, clear, and exact description of the invention, such as will enable others skilled 10 in the art to which it appertains to make and use the same.

This invention is an improvement in apparel, and has particular reference to an overcoat adapted to be worn by horsemen.

An object of the invention is to provide a 15 coat to be interchangeably used for riding and walking, and so constructed that when riding portions thereof may be adjusted to form leg sections, which are secured about 20 the upper portions of the legs in such manner as to protect the same against inclement weather.

Another object is the provision of detachable aprons or skirts designed to be applied 25 to the coat, when riding, so that the same may be employed to cover the pommel and cantle of the saddle.

A further object is the provision of a garment of this character which is simple in 30 construction, easy to manufacture and effective in carrying out the purpose for which it is designed.

The inventive idea involved is capable of 35 receiving a variety of mechanical expressions, one of which, for the purpose of illustrating the invention, is shown in the accompanying drawings, wherein:

Figure 1 is a front elevation of the garment constructed in accordance with the invention, and showing certain parts thereof 40 folded back for purposes of better illustration,

Fig. 2 is a rear elevation of the garment,
Fig. 3 is a section on the line 3-3 of

45 Fig. 2,
Fig. 4 is a section on the line 4-4 of
Fig. 2.

The drawings illustrate what is now believed to be a preferred form of the invention, which comprises the body portion 5, 50 including the usual collar 6 and sleeves 7, the lower ends of which are encircled by straps 8 arranged in guide loops 9, and adapted to be drawn tightly about the wrists of the wearer 55 to provide storm sleeves which will prevent the sleeves of an undergarment from becoming

wet. It will, of course, be obvious that the garment may be made of any desired material, but the same is preferably formed of waterproof cloth. The coat is open at 60 the front as usual and provided along one edge with a plurality of buttons or other suitable fasteners 10 with which coöperate the buttonholes 11 formed along the other edge to fasten the garment about the body 65 of the wearer, the lowermost buttons and buttonholes being only employed when the overcoat is used in the usual manner, as when walking. The back 12 of the body 5 is formed in the lower portion thereof with 70 a slit 13, which extends approximately to the waistline of the garment and along each edge of the slit is secured a flap 14, each of which is provided with a plurality of suitable fasteners 15, and the upper ends of said 75 flaps are enlarged, as indicated at 16, and provided with fasteners 17 for engagement with similar fasteners carried by the body portion, whereby the upper ends of said flaps may be secured thereto. The front 80 edges of the body portion of the garment are also provided with the flaps 18, having fasteners 19 secured thereto below the waistline of the garment for a purpose which will presently appear.

In riding, it is proposed to form leg sections 20 of the lower portion of the body 5 and, to this end, the rear flaps 14 are drawn forwardly between the legs of the wearer and the fasteners 15 thereof are engaged 90 with the fasteners 19 of the front flap 18, whereby said leg sections will be caused to encircle the upper portions of the legs of the wearer and thus effectively cover and protect the same. In this manner it will be 95 obvious that the garment may be readily and quickly transformed from its normal condition into a garment particularly adapted for riding purposes.

Preferably above the waistline the body 100 portion 5 is provided with a belt 21 encircling the same and having its upper edge stitched or otherwise secured thereto, and its ends provided with suitable fasteners 22 adapted for engagement with each other to 105 secure the belt about the body of the wearer. Fastened to the body 5 beneath the belt 21 are a plurality of fasteners 23 to which are adapted to be secured the front and rear aprons or skirts 24 and 25, respectively, the 110 upper edges of which are also provided with fasteners 26 for engagement with the fas-

teners 23, whereby the aprons may be detachably secured to the body and depend from beneath the belt. These aprons or skirts 24 and 25 are employed, respectively, 5 for the purpose of effectively covering the pommel and cantle of the saddle when the rider is seated therein, thus protecting the saddle against inclement weather. It will be apparent that, by the provision of the 10 fasteners 23 and 26, the aprons may be removed when the coat is not being employed as a riding garment.

From the foregoing description, taken in connection with the accompanying drawings, 15 it will be obvious that, with slight changes and alterations, an ordinary overcoat may be transformed into a garment such as described herein, and also that the invention provides a garment which may be interchangeably employed for walking and riding.

What is claimed is:

1. A garment of the class described comprising a body portion open at the front for 25 the entire length and having the rear portion thereof split from the bottom to approximately the waistline, fasteners secured longitudinally of and adjacent the edges of the slit, other fasteners secured to the front

of the body portion and in spaced relation to 30 the edges thereof, the rear fasteners being engageable with the front fasteners to form leg sections when the garment is in use, a belt extending about the garment above the waistline and adjacent the armpits, the belt 35 being secured at its upper edge and having its lower portion free, fasteners carried by the body beneath the belt, and forward and rear aprons extending about the body and having their upper edge portions extending 40 beneath the belt and connected with the fasteners.

2. A garment of the character described comprising a body, a belt extending about the body beneath the arms and secured to 45 the body at its upper edge with its lower edge free, forward and rear aprons extending about the body and having their upper edge portions fitting beneath the belt, and means for releasably securing the upper edge 50 portion of the belt.

In testimony whereof I affix my signature in presence of two witnesses.

DAVID B. WILSON.
